UNITED STATES PATENT OFFICE.

WALTER F. MOORE, OF LIVINGSTON, MONTANA.

BARREL-COVER.

1,214,813.

Specification of Letters Patent.

Patented Feb. 6, 1917.

Application filed April 22, 1916. Serial No. 92,935.

To all whom it may concern:

Be it known that I, WALTER F. MOORE, a citizen of the United States, residing at Livingston, in the county of Park and State 5 of Montana, have invented a new and useful Barrel-Cover, of which the following is a specification.

The device forming the subject matter of this application is a cover for barrels and 10 other receptacles and the invention aims to provide, in a device of this type, novel means for mounting and controlling the lid of the device.

The invention aims to improve the construction of the body and the lid.

Another object of the invention is to provide novel means whereby the lid may be moved to and from open and closed positions by manipulating an actuating element 20 located at one side of the body portion of the cover.

It is within the province of the disclosure to improve generally and to enhance the utility of devices of that type to which the 25 present invention appertains.

With the above and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed, without departing from the spirit of the invention.

In the accompanying drawing:—Figure 1 shows the invention in top plan; Fig. 2 is a side elevation, the lid being closed; Fig. 3 is a side elevation, the lid being opened; 40 Fig. 4 is a cross section taken approximately on the line 4—4 of Fig. 3.

The device forming the subject matter of this application preferably but not necessarily is fashioned from metal throughout 45 and comprises a body 1 of any desired contour, the shape of the body 1 depending upon the shape of the top of the receptacle wherewith the body 1 is to be assembled.

The body 1 includes a top 2 and a depending 50 flange 3, the top 2 being provided with an opening 4, one edge of which may be straight, as indicated at 5.

The invention comprises a lid 7 which may be provided with a straight edge 5a, 55 the straight edge 5a of the lid and the

straight edge 5 of the top 2 of the body 1 being united by means of a hinge 6. When the lid 7 is in a closed position, the lid rests on the top 2 of the body, the opening 4 in the top being of such size that the top 60 will serve as a support for the lid, attention being directed to the dotted line showing of the opening 4 in Fig. 1. In the edge of the top 2 of the body there is formed a notch 8. This notch 8 may be employed 65 for receiving a nail or other securing element whereby the body may be attached to a barrel or other receptacle; or, if desired, the notch 8 may serve as a prize tool seat for receiving a nail or wire which, being used as a lever may be employed for starting the lid 7 toward an open position, should the lid be rusted in place, sealed or otherwise held.

The invention contemplates the use of a transverse actuating shaft embodying ends 70 9 and 16, an intermediate, bail-shaped crank 10, and an operating handle 11 of any desired sort on the end 9. The ends 9 and 16 of the shaft are mounted to rock in the flange 3 of the body 1, slightly below the top 2 and relatively near to the co-operating straight edges 5a and 5 of the lid 7 and the top 2 respectively.

By means of securing elements 12, a keeper 14 is secured to the under face of the lid 7 and in the keeper, the central portion of the bail-shaped crank 10 is slidably received. Intermediate its ends, the keeper 90 14 is spaced apart from the lid 7, so as to define, adjacent the ends of the keeper, shoulders one of which, denoted by the numeral 15 has a function which will be pointed out hereinafter.

In practical operation, the shaft is rotated by manipulating the handle 11, the latter being located exteriorly of the flange 3. The central portion of the bail-shaped crank slides in the keeper 14 and bears 100 against the under face of the lid 7, whereby the lid may be swung to an open position as shown in Fig. 3, it being possible to close the lid by reversing the operation above described. When the lid 7 has been swung to an open position as shown in Fig. 3, the intermediate portion of the bail-shaped crank 10 coacts with the shoulder 15 at the inner end of the keeper 14 and thus the lid is prevented from swinging rearwardly beyond the position shown in Fig. 3 of the drawings.

Having thus described the invention, what is claimed is:—

1. In a device of the class described, a body including a top having an opening; a lid hinged to the top and constituting a closure for the opening, the top having an aperture extended beneath the lid and constituting a prize tool seat; and body carried means operatively connected with the lid to 10 effect an opening and a closing of the lid.
2. In a device of the class described, a body including a top having an opening and a depending flange assembled with the top; a lid hinged to the top and constituting a 15 closure for the opening; a keeper on the under face of the lid; a shaft journaled for rotation in the flange and provided at one end with an exposed operating means, the shaft including a crank slidably received in the 20 keeper.
3. In a device of the class described, a body provided with an opening; a lid hinged to the body and constituting a closure for the opening; a keeper secured to the under face of the lid and having a shoulder; a shaft journaled for rotation in the body and provided with a crank slidably received in the keeper, to effect an opening and a closing of the lid when the shaft is rotated, the intermediate portion of the crank being adapted 25 to coact with the shoulder to prevent a rearward swinging of the lid beyond a predetermined position.

In testimony that I claim the foregoing as my own, I have hereto affixed my signature 30 in the presence of two witnesses.

WALTER F. MOORE.
